UNITED STATES PATENT OFFICE

150,404

DESIGN FOR A COMBINED LAMP AND DESK UNIT

Jesse L. Coen, Washington, D. C.

Application December 16, 1946, Serial No. 135,536

Term of patent 7 years

(Cl. D48—20)

To all whom it may concern:

Be it known that I, Jesse L. Coen, a citizen of the United States of America, residing at Washington, District of Columbia, have invented a new, original, and ornamental Design for a Combined Lamp and Desk Unit, of which the following is a specification, reference being had to the accompanying drawings, forming a part thereof.

In the drawings,

Figure 1 is a detail front elevational view of a combined lamp and desk unit, embodying my new design,

Figure 2 is an end elevational view of the same,

Figure 3 is an end elevational view of the same opposite from Figure 2,

Figure 4 is a sectional view taken on the line 4—4 of Figure 1.

I claim:

The ornamental design for a combined lamp and desk unit, as shown.

JESSE L. COEN.
